UNITED STATES PATENT OFFICE.

JOSEPH WIEDEMEIER, JR., AND ANTON WIEDEMEIER, OF CARROLL, IOWA.

DESIGN FOR A BUTTON-CASE.

SPECIFICATION forming part of Design No. 23,868, dated December 11, 1894.

Application filed December 30, 1893. Serial No. 495,260. Term of patent 7 years.

To all whom it may concern:

Be it known that we, JOSEPH WIEDEMEIER, Jr., and ANTON WIEDEMEIER, citizens of the United States of America, residing at Carroll, in the county of Carroll and State of Iowa, have invented a new and original Design for a Button-Case, of which the following is a specification.

Figure 1 is a side elevation of the complete case and Fig. 2 is a horizontal sectional view of the same.

Referring to the accompanying drawings the frame of the device is seen to be composed of two rectangular top and bottom pieces ornamented by moldings.

B designates upright boards at the corners of the frame placed at right angles to the sides thereof and forming a rectangular space at each corner of the case.

C designates uprights of which two or more are located at each side of the frame at such distance from the uprights B as to admit the drawers A between them.

By this design a set of drawers is located at each side of the device and in the corners are rectangular plain spaces in which no drawers are placed.

The frame is mounted upon the upright D that is supported upon the base D².

What we claim as original in our design is—

The design for a button case substantially as herein shown and described.

JOSEPH WIEDEMEIER, JR.
ANTON WIEDEMEIER.
